UNITED STATES PATENT OFFICE

CHRISTEN SMITH, OF OSLO, NORWAY

BOAT LAUNCHING GEAR

Application filed October 22, 1930. Serial No. 490,389.

This invention relates to boat launching gear and more particularly to the launching gear on ships for launching the ship's life-boats and in which the boats are supported by davits.

According to the invention the davits of each boat are so interconnected as to be movable simultaneously. The davits may be so arranged as to be capable of rotation in a vertical plane and for that purpose may be mounted on a shaft carried in bearings on the deck of the ship, means being provided to rotate the shaft to an extent necessary to bring the boats from the inboard to the outboard positions or vice versa. Stops may be provided to limit the extent of movement of the davits. In a case where a number of boats are arranged on one side of a deck of a ship the davits of all the boats may be interconnected so as to be movable simultaneously. In that case also the davits may be mounted on a shaft having means for rotating it.

In order that the said invention may be clearly understood and readily carried into effect the same will now be described more fully with reference to the accompanying drawing, in which:—

Figure 1 is an elevation of two ship's boats provided with davits in accordance with the invention and in their inboard position.

Figure 2 is a view similar to Figure 1, but showing the boats in the outboard position.

Figure 3 is an end view of Figure 1.

Figure 4 is an end view of Figure 2.

A are the boats, B the davits. The davits are carried at their lower ends on a shaft C which is arranged parallel and close to the edge of the deck and is supported in bearings D. The davits are provided with overhanging portions B¹ from which the boats are suspended. A separate davit is not provided for each end of each boat, but the davits between adjacent boats have two overhanging arms B¹ extending in opposite directions from which the ends of adjacent boats are suspended. The shaft C carries projecting arms E distributed along its length and connected by bars E¹ lying parallel to the shaft, the arms and bars forming a protec-

tive railing to prevent people from falling overboard when the boats are in the outboard position. Fenders F are carried on the shaft C on projecting arms F¹, two such fenders being provided for each boat. The arms F¹ may, if desired, be arranged to act as the aforesaid stops but in the arrangement shown the stops are formed by projecting members C¹ on the shaft C which co-operate with an upstanding member C² on the deck S and act as stops. Flexible members G passing around the boat are arranged to give it stability when it is in the outboard position. They extend between the end of the davit arms and a point on the deck, or as shown, between the davit arms and part of the aforesaid rail and may be allowed to become slack in the inboard position of the boat. Power driven means are arranged at one end of the shaft for rotating it. The means comprises a toothed quadrant H arranged on the end of the shaft C and engaging with a pinion I on a second shaft J which second shaft carries a worm wheel K with which engages a worm L driven by a prime mover M which is shown as an electric motor.

When the boats are in the inboard position as shown in Figures 1 and 3, the aforesaid members G are slack, the fenders F are resting against the outer surface of the boat and the appropriate projecting member C¹ is in contact with the upstanding member C². In order to bring the boats into the outboard position, shown in Figures 2 and 4, the motor M is started to rotate the shaft C in the appropriate direction. The extent of rotation of the shaft is limited by the coming into contact of the other projecting member C¹ with the upstanding member C². In the outboard position the flexible member G passing around the boats have become taut and act to give them stability, and the fenders F are interposed between the boats and the outer wall of the ship against which wall they may rest in that position. In order to return the boats to the inboard position the shaft is rotated in the reverse direction by the electric motor M.

What I claim and desire to secure by Letters Patent of the United States is:—

1. Ships' boat launching gear comprising davits, a shaft connecting same, boat-fenders, means for rotating said shaft to move said davits and fenders into position and arms projecting from said shaft for carrying said boat-fenders.
2. Ships' boat launching gear comprising davits, a shaft connecting said davits, means for rotating said shaft to move said davits, and a protective rail moved into position by said shaft when it is rotated to move said davits to the outboard position.
3. Ships' boat launching gear as in claim 2, in which the protective rail is carried on arms projecting from said shaft.
4. Ships' boat launching gear comprising davits for more than one boat, a shaft having said davits mounted on it in spaced relationship, oppositely extending boat supporting arms on the intermediate davits, means for rotating said shaft, boat fenders carried on arms projecting from said shaft, a protective rail carried on other arms projecting from said shaft, said protective rail and boat fenders being moved into position by said shaft when it is rotated to move said davits to the outboard position.
5. Ships' boat launching gear comprising a shaft, bearings for said shaft for mounting adjacent the edge of the deck of the ship, a number of davit arms carried by said shaft and for supporting a number of boats, means for partially rotating said shaft so as to swing all of said boats from an inboard position into an outboard position simultaneously and vice versa, said rotational means being situated at one end of said shaft and fenders on said shaft rotatable therewith so as to engage the sides of the boats when the boats are in an inboard position and also when the boats are in an outboard position.
6. Ships' boat launching gear comprising a shaft, bearings for said shaft for mounting adjacent the edge of the deck of the ship, a number of davit arms carried by said shaft and for supporting a number of boats, means for partially rotating said shaft so as to swing all of said boats from an inboard position into an outboard position simultaneously and vice versa, said rotational means being situated at one end of said shaft, and a railing carried by said shaft and rotatable therewith, said railing being moved into its operative position on the shaft being rotated to swing the boats into an outboard position.

In testimony whereof I have signed my name unto this specification.

CHRISTEN SMITH.
